ATTORNEY.

UNITED STATES PATENT OFFICE.

DOMENICO VIOLA, OF PHILADELPHIA, PENNSYLVANIA.

CIGARETTE BOX.

Application filed June 13, 1927. Serial No. 199,109.

This invention relates generally to dispensing boxes and it has more particular reference to that type adapted to release individual cigarettes as required, such as described in my prior application Serial Number 78,106, filed December 29th, 1925. Boxes of the typified character while satisfactory in many respects generally possess the disadvantage that the contained cigarettes can 5 be illicitly removed, with attendant annoyance and loss to the owner if said cigarettes be of some choice or particular brand.

The primary object of my invention, accordingly, is to provide a box for cigarettes, 15 cigars, and so forth, of the type referred to, which is readily locked and closed, against illicit tampering with the contents thereof, in a manner that puzzles the skill and wits of unauthorized persons to detect how said 20 box may be opened.

Other objects are to provide a cigarette box, as referred to in the preceding paragraph, which embodies dispensing or releasing means for individual cigarettes; a novel 25 locking means; and, relatively movable elements designed to foil unauthorized persons making any effort to improperly open said box.

With the foregoing and other objects in 30 view, this invention consists essentially in the novel construction, arrangement and combinations of parts hereinafter fully described, illustrated on the accompanying sheet of drawings, and tersely stated as far 35 as features and scope are concerned by the appended claims.

In the drawings:—

Figure 1 is a perspective view of a cigarette box embodying the present improvements.

Figure 2 is a vertical transverse section taken on the plane indicated by the arrowed lines 2—2 in Figure 3; and showing the movable portion elevated in dot-and-dash 45 lines.

Figure 3 is a longitudinal section taken as indicated by the lines 3—3 in Figure 2.

Figure 4 is an underside plan of the means effective to release and dispense individual 50 cigarettes, removed from the box; and

Figure 5 is an underside plan view of the complete cigarette box.

Like reference indicia designate the same or corresponding parts in all the views.

Referring more in detail to the several

views my novel cigarette box is comprehensively designated by the numeral 6—Figure 1—and it will be observed that—in the embodiment chosen for illustration—it is rectangular in shape. This box 6 comprises a reciprocable inner shell 7 to which the closure top 8 is firmly secured and provided with a centrally located longitudinal slot 9, that snugly accommodates the cigarette dispensing member 10, when said inner shell is in the normal or closed position shown.

The outer or relatively stationary casing 11 of the cigarette box 6 includes a base 12, conveniently—though not essentially—fitted with supporting elements 13 at the lower angular corners, and which may be conventionally provided with non-slip under surfaces of suitable material such as baize, rubber or the like.

The means effective to retain the parts 7 and 11 in operative relation comprise plate members 14 set in the lower edge of the shell 7, and having tongues 15 that engage vertical slots 16 formed in the inner wall of the stationary casing 11 along conventional lines, and affording provision for limited movement of said shell relative to the stationary portion.

The inner shell 7 is provided with opposed downwardly converging filler blocks 17 which are adapted to slide vertically of the dispensing member 10 in consecutively elevating the cigarettes 18 to deposit an individual one in the longitudinally grooved upper edge 19 of said member, as will be well 95 understood on reference to Figure 2, more particularly.

Locking of the inner shell 7 to the outer casing 11 to prevent reciprocation of the latter—in effecting ejection of cigarettes 18 illicitly—is effected through the medium of a slidable bolt 20 engaging a transverse slot 21 in the bottom closure member 22. Particular attention is directed to the fact that the bolt 20 is preferably of rectangular cross section and that it is of a length so as not to be removable from cooperative engagement in the complementarily shaped recesses 23, 24—Figure 2—formed in the lower side walls of the portion 11; whereas it is of a cross section, slidably free—but in no respect loose—in the associated recesses. The bolt 20 is also provided at one end with a centrally located finger or projection 25 having an inclined under face 26 which is 115

adapted to engage a suitably configured hasp 27 securely attached to the underside of one of the filler blocks 17 aforesaid; hence it will be readily understood that when the parts 5 23, 24 and 26, 27 are in engagement that the shell 7 and outer casing 11 are frictionally locked together, while no markings or visible means are apparent, indicative that the bolt 20 is the element movable in order to release 10 said parts in affecting the dispensing of cigarettes.

In order to render my novel box effective against illicit purloining of the contained cigarettes 18 and to better "fool" those attempting to open the same, I provide the bottom closure member 22 with relatively staggered dovetail-section ribs 28, 29, having freely slidable members 30 thereon. In addition to the members 30, I fit the closure 20 member 22 with pivoted finger pieces 31 having rounded free ends 32 adapted to jamb with the correspondingly notched out parts 33 of said members 30. Obviously, the slidable members 30 and finger pieces 31 25 may be variously patterned and finished to better "fool" anyone endeavoring to illicitly ascertain their possible combination in affecting release of the shell 7 relative to the part 11, as indicated by dotted lines in Figure 5; hence I do not limit myself to the specific aggroupment of such parts shown. It is also to be understood that I preferably make the relative cooperative and locking 30 portions of materials unaffected by normal usage while affording adequate frictional engagement between the bolt 26 and hasp 27, so that they may not be accidentally or inadvertently released.

From the foregoing it is thought that the 40 use and effectiveness of my novel lock box for cigarettes, cigars and so forth, will be

apparent without further explanation herein, while the exterior portions may be patterned and finished in numerous manners without departing from the spirit or scope 45 of the invention as defined by the subjoined claims.

Having described my invention what I claim is—

1. In a dispensing device for individual 50 cigarettes or the like and comprising a stationary outer casing and base with a relatively telescopic inner shell embodying filler blocks affording storage for cigarettes, and a member slidable laterally of the aforesaid 55 base and adapted to frictionally engage in apertures in the walls thereof to effect locking of the inner shell thereto.

2. In a dispensing device for individual 60 cigarettes or the like and comprising a stationary outer casing and base with a relatively telescopic inner shell embodying filler blocks affording storage for cigarettes, and a rectangular-section bolt slidable laterally in the casing base and adapted to frictionally 65 engage complementary apertures therein in effecting locking of the inner shell thereto.

3. In a dispensing device for individual 70 cigarettes or the like and comprising a stationary outer casing and base with a relatively telescopic inner shell embodying filler blocks affording storage for cigarettes, and a rectangular section bolt slidable laterally in the casing base and adapted to frictionally 75 engage complementary apertures therein, said bolt having a longitudinally directed finger adapted to enter a hasp-secured to the underside of the inner shell-in effecting locking of the parts together.

In testimony whereof I have signed my 80 name hereunto the fourth day of June, 1927.

DOMENICO VIOLA.
